GLUING PRESS

Edward J. Klassen, Los Angeles, Calif.

Application August 17, 1942, Serial No. 455,052

20 Claims. (Cl. 144—281)

This invention relates generally to presses for applying pressure and heat to members which are being glued together to expedite setting of the glue.

The invention has particular present application to the gluing of plywood skins on a wood construction airfoil, and will, for illustrative purposes only, be described in that connection, though without necessary limitation thereto since it has various other applications. The glue now used for such purposes is of a phenolic plastic type, whose setting time is greatly reduced in the presence of heat, and it accordingly becomes desirable to apply heat to the exterior surface of the plywood after the latter has been applied to the glue coated skeleton frame of the airfoil. As in any gluing operation, it is also desirable to apply pressure, and it is therefore the combined purpose to apply both heat and pressure to the glued members.

The general object of the present invention is accordingly the provision of an improved press designed to operate on such a typical member as an airfoil and to apply both pressure and heat to the portions of the plywood skin that are in engagement with and have been glued to the skin supporting surfaces of the airfoil framework.

Considered broadly, the present invention provides a heating means which is applicable to the plywood skin that has just been glued over the skeleton frame work, a flexible curtain which overlies said heating means, and a pneumatic means such as an inflatable bag which exerts a pressure through the flexible curtain against the heating means, and so presses the latter evenly against the plywood skin. The flexible curtain and heating means are designed to accommodate themselves readily to the shape of the airfoil, or other member being glued, permitting the application of uniform pressure to the heating means, and uniform application of the heating means to the skin.

With this general discussion in mind, the invention will best be described in connection with the following detailed description of one present illustrative embodiment thereof, reference for this purpose being had to the accompanying drawings, in which:

Fig. 1 is a perspective view of a press in accordance with the invention;

Fig. 2 is a vertical transverse section on plane 2—2 of Fig. 1, the view being conventionalized to omit illustration of the taper of the table and airfoil;

Fig. 3 is a horizontal section taken in accordance with line 3—3 of Fig. 2;

Fig. 4 is a detail section on line 4—4 of Fig. 1, but with the press assumed to be in closed position;

Fig. 5 is an enlarged detail of parts enclosed within the circle 5 of Fig. 3;

Fig. 6 is a section on line 6—6 of Fig. 5;

Fig. 7 is a detail section on line 7—7 of Fig. 2;

Fig. 8 is a section on line 8—8 of Fig. 7;

Fig. 9 is a section on line 9—9 of Fig. 8;

Fig. 10 is a section taken on line 10—10 of Fig. 9;

Fig. 11 is a section in the same plane as Fig. 10 but showing the intersection of the steam bar 52 that is over the spar with the end transverse steam bar 54;

Fig. 12 is a section in the same plane as Fig. 10 but showing the parts at an outside corner of the heating gridwork;

Fig. 13 is an enlarged detail of a portion of Fig. 2; and

Fig. 14 is a section similar to Fig. 13 but showing a modification.

Referring now to the drawings, I show at 20 a suitable supporting table or bench having a plane, horizontal upper surface 21, and furnished with suitable legs 22. This table is provided with a hinged cover member 23, shaped on its under side to conform to the contour of the wooden skeleton frame S of the airfoil, which is to be taken by the press.

Airfoil skeleton frame S may comprise typically, a plurality of longitudinally spaced transverse webs 24, a longitudinally extending nose block 25, a longitudinally extending central spar 26, and a trailing edge piece 27. In the usual construction, the nose block, spar and trailing edge piece consist of continuous one-piece members 40 extending the length of the airfoil, while the transverse webs 24 each consist of two members interrupted by the spar. In accordance with the construction here illustrated, the webs 24, which are relatively thin, are braced along their upper and lower marginal edges with cap strips 27 (Figs. 2, 8 and 9). The particular airfoil here chosen for illustrative purposes has a plane or flat bottom surface and a curved upper surface, as illustrated in Fig. 2, although the particular shape of the airfoil is of course not limitative on the invention, it being understood that the press will be built to conform in any given instance. Numerals 30 and 31 designate the upper and lower plywood skins which have been applied to the upper and lower sides of the skeleton

45

45

55

frame S of the airfoil, these members consisting usually of three-ply layers of suitable material, though for simplicity of illustration they are here conventionally illustrated as single layers, and it being understood that a suitable glue has been coated on the engaging surfaces between the skeleton frame and the plywood surface layers 30 and 31 prior to application of the latter. As heretofore stated, the glue used is understood to be of a type whose setting time is materially reduced in the presence of heat.

Arranged on the upper surface 21 of table 20, in a lay-out conforming to the various members making up the skeleton frame S, is a lower grid-work 35 of heat conductive metal embodying a plurality of longitudinal bars 36 and transverse bars 37, which include or incorporate a heating agency, of any suitable or desired type. As here illustratively shown, this heating agency consists of steam passages running longitudinally of the grid-work bars, as more fully to be described presently. As will be understood, these bars 36 and 37 of the grid-work are so arranged as to engage the lower plywood skin 31 directly beneath the under surfaces of skeleton frame members 25, 26, 27, and 24, the skin spanning between the bars of the grid-work between said members.

Attached to the rearward longitudinal edge of table 20, as at 40, is a flexible sheet 41, preferably formed of highly heat conducting sheet metal, which is stretched tightly over the top side of the airfoil so as to support it firmly in position, and is detachably fastened at the front edge of the table. In the present illustrative form of the invention, the table is provided at its front longitudinal edge with an inclined face 42, formed at such an angle that the sheet 40 pulled down taut over the airfoil will lie substantially flat against it. In somewhat similar manner, the table is preferably formed adjacent its rearward edge with a somewhat elevated portion topped by an inclined face 43, forming a substantial continuation of the airfoil, and against which the sheet 41 may lie substantially flat. The front longitudinal edge of the sheet 41 is wrapped around and fastened in any suitable manner to a longitudinal edge piece 45, which carries studs 46 detachably engageable by the eyes 47 of a suitable clamp device 48 secured to the table and operable to stretch the sheet 41 taut over the airfoil. The clamp devices 48 may be of any well known or appropriate type adapted to perform the function described, though I have here indicated an eccentric type of clamp by which the tension exerted on the sheet may be adjusted. Thus each clamp device 48 embodies a plate 48a formed with the aforementioned eye 47, a circular strap 48b carried by plate 48a and surrounding an eccentric 48c and a shaft 48d on which the eccentric is tightly mounted, and which is itself pivotally mounted in a bracket 48e affixed to the table, the shaft being fitted with an operating handle 48f by means of which the eccentric may be rotated to draw the plate 48a downwardly and thereby tense the sheet 41.

Applicable to skeleton framework S, over the stretched sheet 41, is an upper grid-work 50 of heat conducting metal embodying parallel longitudinal bars 51 and transverse bars 52, all generally similar to the lower grid-work 35, excepting that the upper grid-work is formed to conform to the top side curvature of the airfoil. Thus the bars 51 and 52 of grid-work 50 are so

arranged as to conform to the upper surface of the plywood skin 30 applied over skeleton frame members 25, 26, 27 and 24, and to engage flexible sheet 41 directly over said members, the sheet 51 and plywood skin spanning between said members. Upper grid-work 50 is preferably, though not necessarily, carried by a flexible curtain 55 which extends over it, and which is in turn carried by cover 23. This curtain 55 preferably comprises a plurality of longitudinally extending, articulated wood strips or slats 56 mounted, as by means of adhesive, or any suitable fastening means, on the lower surface of a flexible fabric sheet 57. The strips are preferably substantially rectangular in cross-section, but with their sides tapered, where the curtain is curved, so as to be radial of the center of curvature. These strips are mounted on sheet 57 with sufficient clearances between them to permit the strips to move relatively to one another whereby the curtain may conform to the exact contour of the airfoil.

The curtain 55 is carried by the aforementioned pivoted cover 23, which will now be described in more detail. This cover comprises a large metal casting, shaped in general contour to conform to the shape of the top side of the airfoil, and formed at the rear with downward projections 60 through which it is pivotally mounted, as at 61, on mountings 62 secured to the rearward side of the table. Preferably, these downward projections 60 have rearward extensions 63 carrying counterweights 64 for the cover.

In the particular embodiment of the invention here shown for illustration, the cover has front and rear walls 66 and 67, end walls, one of which, designated at 68, is removable (see Fig. 1), an upper wall 69, and wall 70 spaced a short distance below the latter. Removable end wall 68 is here shown as formed with end flanges 68a bolted to ears 68b extending from the sides of the cover. The side and end walls of the cover are formed with marginal inturned flanges 71 at their edges (Figs. 2, 8 and 12) the front and rear end strips 56a of curtain 55 having projections 56b which overlie the flanges 71 extending from the side walls of the cover, and the ends of the strips 56 being notched on the underside, as at 56b, so as to overlie the flanges 71 formed on the end walls of the cover (Fig. 4), the parts preferably being so dimensioned that the lower face of the flexible curtain comprising the strips 56 comes no higher than the underside of the flanges 71. When the cover of the press is up, the curtain strips are supported by the flanges 71, but when the cover is closed, the engagement of the heating grid-work with the air-foil elevates the strips somewhat above flanges 71 (Figs. 2, 4 and 13), so that said flanges will not interfere with application of pressure through the curtain.

A flexible sheet metal plate 72 lies flat against and covers the upper surface of curtain 55, being preferably attached to a strip 56 of the curtain; thus, Fig. 8 shows the plate 72 to be attached, as by screws 73, to the strip 56 of the curtain which is over the spar 26 of frame S. This method of attachment permits the plate 72 and curtain 55 to bend together and conform to one another. Mounted inside cover 23, adjacent its side and end walls, and below partition 70, is a rectangular frame comprising a top member 74 and bottom member 75, suitably fastened to one another, as by screws or the like, the members

of said frame adjacent side walls 66 and 67 being preferably fastened to said walls, as by screws 75a (Fig. 13). Clamped between the members 74 and 75 are the edges of a flexible fabric wall 77 which lies adjacent the upper surface of curtain 55 (Fig. 13). An inflatable pneumatic bag 78, of rubber, rubberized fabric, or other suitable material, is placed between the fabric wall 77 and the wall 70 of cover 23. This bag 78 has a filling tube or stem 79 extending through end plate 68 of cover 23 and will be understood to contain a suitable check valve, like a conventional tire valve. The flexible sheet metal plate 12 and flexible fabric wall 77 protect the lower wall of the bag.

As previously stated, the bars 36, 37, 51 and 52 of lower and upper grid-works 35 and 50 are provided with heating means or provisions, which in the specific embodiment of my invention here chosen for illustrative purposes comprise longitudinal steam passages. Fig. 6 is a typical cross-section of one of bars of the lower grid-work, and shows the bar, in this instance a lower bar 37, to consist of a base plate 90 secured to the upper side of table 20, transversely spaced side bars or members 91, and a cover plate 92. The several described members define a steam passageway P. Fig. 5 shows a typical corner construction, and illustrates how the several members making up each bar are arranged in abutting relation to provide a continuous steam passageway P extending around the corner formed by the two abutting bars 36 and 37.

Figs. 5 and 6 also show a steam discharge port 95, of which there are a suitable number, leading from passageway P outwardly through the outside side member 91 of the bar.

Fig. 8 shows a cross-section of a steam bar 51 of the upper heating grid-work, it being understood that bars 51 and 52 are of similar cross-section, and shows how said bar may be carried by flexible curtain 55. It may be noted at this point that it is not at all essential that the upper heating grid-work be carried by curtain 55, though added convenience results from such arrangement. The bar 51, as here shown, includes a base or mounting plate 100 of a width preferably nearly three times the width of a strip 56 of curtain 55, and substantially covering three of said strips, being fastened, as by screws 101, to the two outside strips and bridging across the intermediate one.

Bar 51 also includes a pair of transversely spaced side bars or members 102 and a cover plate 103, the several described members defining a steam passageway P. The members are held in assembly by headed studs 104 which extend downwardly through suitable drill holes in plate 100 and bars 102 and thread into cover plate 103. The heads 105 of the studs are loosely accommodated within pockets 106 formed in the strips 56, and the studs are of such length that when the plate 103 is not being pressed downwardly against the airfoil, said plate 103 together with the side members 102 are suspended by the studs whose heads 105 are then in engagement with the upper surface of plate 100, with some slight looseness or clearance between the members 102 and the underside of plate 100. However, when plate 103 is in engagement with the airfoil, or rather, with the flexible sheet 41 stretched over the airfoil, and downward pressure is exerted on curtain 55 from above, in a manner later to be described, the plate 103, studs 104 and side members are elevated rela-

tively to curtain 55, as shown in Fig. 8, with the members 100, 102 and 103 defining the closed steam passageway P. I prefer that the studs 104 carrying the steam bar that extends over spar 26 be closely fitted by the corresponding stud holes 104a, but that the studs 104 carrying the remaining steam bars be loosely fitted within the corresponding stud holes 104b, so as to provide a certain looseness of fit such as will permit some accommodation of the members.

Fig. 11 shows the intersection between the longitudinal upper steam bar 51 that overlies the spar and the end transverse upper steam bar 52. As illustrated, one of the side members 102 of the transverse bar 52 is formed with a gap 110, which receives the end portions of side members 102 of the longitudinal bar 51. The clearance spaces between the end portions of members 102 of bar 51 and the end portions of the interrupted member 102 of bar 52 are closed by means of curved spring elements 112 fastened to the end portions of the interrupted member 102 of bar 52 and engaging the members 102 of the bar 51, in the manner clearly shown in Fig. 9.

In Figs. 9 and 10 is shown an intersection of an upper longitudinal steam bar 51 and an upper transverse steam bar 52 at the location of the intersection of spar 26 with a transverse web 24, where the members form a complete cross. Here the two side members 102 of the transverse bar 52 are formed with gaps 116, the end portions of the latter members 102 being received within the gaps 115, all as clearly shown in Fig. 10. The clearance spaces between the adjacent end portions of the several members 102 are then closed by means of curved spring elements 116, of the type previously described (Fig. 10).

Steam is introduced to the steam passageways P of the upper and lower grid-works of the press through any suitable steam connections. I here show a steam supply pipe 120 having a control valve 121 (Fig. 1) and provided with a T-coupling 122, one branch of which is coupled to an inlet conduit 123 opening through a side member 102 of the end transverse steam bar of the lower grid-work into steam passageway P. (Fig. 3.) The other branch of coupling 122 is connected via flexible steam conduit 124 to an inlet conduit 125 opening through side member 102 of the end transverse steam bar of the upper grid-work into the steam passageway, therewithin.

Cover 23 is furnished with a handle 130 by means of which it may be manually raised and lowered, and with eyes 131 supporting the upper ends of links 132, the lower ends of which are screw-threaded to receive clamp nuts 133, above which are washers 134. The front edge of the table has notched brackets 135 which receive the links 132 when the cover is lowered, and the cover may be clamped down tightly by thereafter setting up nuts 133 against the undersides of the brackets. Of course, any other type of clamping device may be substituted for the simple arrangement here indicated.

Operation of the press is as follows: The skeleton frame S of the airfoil with the plywood skin layers 30 and 31 freshly glued thereto is placed in proper alignment on lower heating grid-work 35. Flexible sheet 41 is then stretched over the top side of the airfoil and clamped in place, thereby securing the airfoil in position and pressing it down firmly on lower grid-work 35. Cover 23 is then lowered and clamped down tightly by means of links 132 and nuts 133, after which

pneumatic bag 78 is inflated to a suitable pressure, which may vary with different conditions, but which in any case must be adjusted to apply the necessary downward pressure for the conditions in hand. The inflated bag transmits downward pressure through fabric wall 77 and flexible plate 72 equally over the entire flexible curtain 55, which accommodates itself to the contour of the airfoil, and presses the bars 51 and 52 of upper heating grid-work 50 firmly and evenly down against the flexible sheet 41 stretched over the upper plywood skin. The heating bars come directly over the longitudinal and transverse members of skeleton frame S and span the spaces between them, so that no pressure will be applied to the plywood where it is unsupported by the frame. Each heating bar of the grid-work is pressed down by the pneumatic bag 78, acting through flexible curtain 55, accurately and uniformly along the plywood skin over the skeleton frame member directly below. Accommodation of the upper heating grid-work to the curved contour of the airfoil is enhanced by inherent natural flexibility of the grid-work, and by the flexible suspension of the grid-work through the hanger studs 104. Moreover, the grid-work is capable of "working" to relieve strains, not only in the course of application under pressure to the airfoil, or other work, but also during heating, owing to the looseness of fit of all of the heating bars, excepting those over the central spar 26, on the supporting studs 104. The grid-work may thus be regarded as made up of flexible relatively movable heating elements, flexibly supported from the curtain 55, and capable, by virtue of such flexibility and capacity for relative movement, of nice accommodation to the contour of the work under the combined effects of heat and pressure.

The upper heating grid-work being thus uniformly pressed down on the airfoil, steam is admitted to the steam passages of the upper and lower grid-works, so as to heat the grid bars and cause heat to be transmitted to the glued joints. The sheet 41 between the upper grid-work and the airfoil is of highly heat conductive metal, and readily transmits the applied heat to the glued skin of the airfoil. Steam is permitted to escape continuously from the passageways P of the upper and lower grid-works, as by means of the vents 95 indicated in Figs. 5 and 6. If desired, further steam vent passageways 95a may be provided in the upwardly projecting portion of the table along the rearward edge thereof (see Fig. 2), being placed in alignment with the steam vents 95 in the lower steam bar 36. This permits the steam discharged from vents 95 of rearward lower bar 36 into the relatively confined space at the rearward edge of the table to escape somewhat more readily. The heat and pressure having been applied for a suitable period, the steam supply is cut off, the press opened, and the glued airfoil removed. The press thus accomplishes simultaneous uniform application of heat and pressure, such as will rapidly set the glue, to both plywood skins of the airfoil, but restricted to the areas of the skins directly braced by the skeleton frame S.

Fig. 14, which is a view similar to Fig. 13, shows a modified arrangement for protection of rubber bag 78 from flexible plate 72 and curtain 55. In this form, the two frame members (Fig. 13) are replaced by a single frame 120, to the upper edge of which is attached the upper edge of a curtain 121 of fabric such as canvas. The curtain 121 hangs downwardly along the inner face

of member 120, and its lower portion is wrapped and fastened about a wooden strip 122, of such cross-sectional form as shown, and adapted to fill in the corner between the metal sheet 72 and the member 120. This provision prevents the bag 78 from getting down around the edge of the sheet 72. It will be understood that the provisions shown in Fig. 14 may be employed along both side walls of the cover, and along both end walls as well.

It will of course be understood that the drawings and description are merely of a specific illustrative embodiment of the invention, which may take various other forms or incorporate various changes in design, structure and arrangement all without departing from the spirit and scope of the appended claims.

I claim as my invention:

1. In a gluing press, the combination of a support for the article to be glued, heating means applicable over said article on said support, a flexible curtain stretched over said heating means, means flexibly supporting said heating means from said curtain, and pneumatic means for exerting uniform pressure over the area of said curtain covering said heating means to press said heating means uniformly against said article.

2. In a gluing press, the combination of a support for the article to be glued, heating means applicable over said article on said support, a curtain comprising a plurality of parallel slats secured in mutually spaced relation to a flexible sheet stretched over said heating means, and pneumatic means for exerting uniform pressure over the area of said curtain covering said heating means to press said heating means uniformly against said article.

3. In a gluing press, the combination of a support for the article to be glued, a flexible metal sheet adapted to be stretched over said article on said support and fastened to said support, heating means applicable against said flexible sheet, a flexible curtain stretched over said heating means, and pneumatic means for exerting uniform pressure over the area of said curtain covering said heating means to press said heating means uniformly against the flexible metal sheet stretched over said article.

4. In a gluing press, the combination of a support for the article to be glued, a flexible metal sheet adapted to be stretched over said article on said support and fastened to said support, heating means comprising a plurality of relatively movable heating elements applicable against said flexible sheet, a flexible curtain comprising a plurality of mutually spaced relatively movable slats secured to a flexible sheet stretched over said heating means, and pneumatic means for exerting uniform pressure over the area of said curtain covering said heating means to press said heating means uniformly against the flexible metal sheet stretched over said article.

5. In a gluing press, the combination of a support for the article to be glued, heating means applicable over said article comprising a plurality of flexibly interconnected heating bars conforming to the contour of the upper side of said article, a flexible curtain stretched over said heating bars comprising a plurality of articulated elements, and pneumatic means for exerting uniform pressure over the area of said curtain covering said heating bars to press said bars uniformly against said article.

6. In a gluing press, the combination of a support for the article to be glued, heating means ap-

plicable over said article comprising a flexible gridwork of articulated heating bars conforming to the contour of the upper side of said article, a flexible curtain stretched over said heating bars comprising a plurality of articulated elements, and pneumatic means for exerting uniform pressure over the area of said curtain covering said heating bars to press said bars uniformly against said article.

7. In a gluing press, the combination of a support for the article to be glued, heating means applicable over said article comprising a plurality of flexibly interconnected heating bars conforming to the contour of the upper side of said article, a flexible curtain stretched over said heating bars comprising a plurality of articulated elements, means flexibly supporting said heating bars from said flexible curtain, and pneumatic means for exerting uniform pressure over the area of said curtain covering said heating bars to press said bars uniformly against said article.

8. In a gluing press, the combination of a support for the article to be glued, heating means applicable over said article comprising a plurality of hollow, intercommunicating and flexibly interconnected steam bars conforming to the contour of the upper side of said article, a flexible curtain stretched over said steam bars comprising a plurality of articulated elements, and pneumatic means for exerting uniform pressure over the area of said curtain covering said heating bars to press said bars uniformly against said article.

9. In a gluing press, the combination of a support for the article to be glued, heating means applicable over said article comprising a plurality of flexibly arranged heating bars conforming to the contour of the upper side of said article, a flexible curtain stretched over said heating bars comprising a plurality of mutually spaced and relatively movable articulated elements, and pneumatic means for exerting uniform pressure over the area of said flexible curtain covering said heating bars whereby said bars are pressed uniformly against said article by pressure transmitted through said articulated elements.

10. In a gluing press, the combination of a bottom support for the article to be glued, a flexible metal sheet stretched over said article to secure it firmly to said support, heating means applicable to said article through said metal sheet comprising a plurality of heating bars conforming to the contour of the upper side of said article, a flexible curtain stretched over said heating bars comprising a plurality of articulated elements, and pneumatic means for exerting uniform pressure over the area of said curtain covering said heating bars to press said bars uniformly against said flexible metal sheet stretched over said article.

11. In a gluing press, the combination of a support for the article to be glued, heating means applicable over said article comprising a plurality of flexibly arranged heating bars conforming to the contour of the upper side of said article, a flexible curtain stretched over said heating bars comprising a plurality of mutually spaced, articulated slats, and pneumatic means for exerting uniform pressure over the area of said curtain covering said heating bars to press said bars uniformly against said article.

12. In a press for a glued article comprising a skin applied over a skeleton frame that has a plurality of frame members providing supporting surfaces for said skin, the combination of means adapted to support said article with its

said skin exposed, a flexible metal sheet adapted to be stretched over said exposed skin of said article to secure the article in position, heating means applicable to the skin of said article through said flexible metal sheet comprising a plurality of heating bars conforming to the contour of said article and arranged to engage said flexible metal sheet only in positions corresponding to the locations of said supporting surfaces of said skeleton frame, a flexible curtain stretched over said heating bars comprising a plurality of articulated slats, and pneumatic means for exerting uniform pressure over the area of said curtain covering said heating bars to press said bars uniformly against said article through said flexible sheet stretched over said article.

13. In a press for a glued article comprising a skin applied on a skeleton frame that has a plurality of frame members providing supporting surfaces for said skin, the combination of means adapted to support said article with its said skin exposed, a flexible metal sheet adapted to be stretched over said exposed skin of said article to secure the article in position, heating means applicable to the skin of said article through said flexible metal sheet comprising a plurality of heating bars conforming to the contour of said article and arranged to engage said flexible metal sheet only in positions corresponding to the locations of said supporting surfaces of said skeleton frame, a flexible curtain stretched over said heating bars comprising a plurality of articulated slats, means supporting said heating bars from said curtain, and pneumatic means for exerting uniform pressure over the area of said curtain covering said heating bars to press said bars uniformly against said flexible sheet stretched over said article.

14. In a press for a glued article comprising a skin applied over a skeleton frame that has a plurality of frame members providing supporting surfaces for said skin, the combination of means adapted to support said article with its said skin exposed, a flexible metal sheet adapted to be stretched over said exposed skin of said article to secure the article in position, heating means applicable to the skin of said article through said flexible metal sheet comprising a plurality of heating bars conforming to the contour of said article and arranged to engage said flexible metal sheet only in positions corresponding to the locations of said supporting surfaces of said skeleton frame, a cover member movable toward and from said article, a flexible curtain carried by said cover member over said last named heating bars and comprising a plurality of articulated elements engageable with said heating bars, said heating bars being applicable to said flexible sheet stretched over said article by movement of said cover member toward said article, and an inflatable pneumatic bag enclosed within said cover adapted to exert uniform pressure over the area of said curtain covering said heating bars to press said bars uniformly against said sheet stretched over said article.

15. In a press for a glued article comprising a skin applied over a skeleton frame that has a plurality of frame members providing supporting surfaces for said skin, the combination of means adapted to support said article with its said skin exposed, a flexible metal sheet adapted to be stretched over said exposed skin of said article to secure the article in position, heating means applicable to the skin of said article through said flexible metal sheet comprising a

plurality of heating bars conforming to the contour of said article and arranged to engage said flexible metal sheet only in positions corresponding to the locations of said supporting surfaces of said skeleton frame, a cover member movable toward and from said article, a flexible curtain carried by said cover member over said last named heating bars and comprising a plurality of articulated elements engageable with said heating bars, said heating bars being applicable to said flexible sheet stretched over said article by movement of said cover member toward said article, means supporting said heating bars from said curtain, and an inflatable pneumatic bag enclosed within said cover adapted to exert uniform pressure over the area of said curtain covering said heating bars to press said bars uniformly against said sheet stretched over said article.

16. In a press for a glued article comprising skins applied over opposite faces of a skeleton frame that has a plurality of frame members providing supporting surfaces for said skins, the combination of a support, heating means on said support comprising a plurality of heating bars conforming to the contour of one face of said article and arranged to engage the corresponding skin of said article in positions corresponding to the locations of the supporting surfaces of said skeleton frame for that skin, a flexible metal sheet adapted to be stretched over the other skin of said article positioned on said heating bars to secure the article in position thereon, heating means applicable to said other skin of said article through said flexible sheet comprising a plurality of heating bars conforming to the contour of the other face of said article and arranged to engage said flexible sheet only in positions corresponding to the locations of said supporting surfaces of said skeleton frame for said other skin, a cover member movable toward and from said article, a flexible curtain carried by said cover member over said last named heating bars and comprising a plurality of articulated elements engageable with said heating bars, said heating bars being applicable to said flexible sheet stretched over said article by movement of said cover member toward said article, and an inflatable pneumatic bag enclosed within said cover adapted to exert uniform pressure over the area of said curtain covering said heating bars to press said bars uniformly against said sheet stretched over said article.

17. In a press for a glued article comprising skins applied over opposite faces of a skeleton frame that has a plurality of frame members providing supporting surfaces for said skins, the combination of a support, heating means on said

support comprising a plurality of heating bars conforming to the contour of one face of said article and arranged to engage the corresponding skin of said article in positions corresponding to the locations of the supporting surfaces of said skeleton frame for that skin, a flexible metal sheet adapted to be stretched over the other skin of said article positioned on said heating bars to secure the article in position thereon, heating means applicable to said other skin of said article through said flexible sheet comprising a plurality of heating bars conforming to the contour of the other face of said article and arranged to engage said flexible sheet only in positions corresponding to the locations of said supporting surfaces of said skeleton frame for said other skin, a cover member movable toward and from said article, a flexible curtain carried by said cover member over said last named heating bars and comprising a plurality of articulated elements engageable with said heating bars, said heating bars being applicable to said flexible sheet stretched over said article by movement of said cover member toward said article, means supporting said heating bars from said curtain, and an inflatable pneumatic bag enclosed within said cover adapted to exert uniform pressure over the area of said curtain covering said heating bars to press said bars uniformly against said sheet stretched over said article.

18. In a gluing press, the combination of a relatively flexible heating means applicable over the article to be glued and adapted to conform to the contour thereof, a curtain of parallel, mutually spaced and individually movable slats over and applicable to said heating means, and means for applying a uniform pressure to said curtain of slats.

19. In a gluing press, the combination of a relatively flexible heating means applicable over the article to be glued and adapted to conform to the contour thereof, a curtain of parallel, mutually spaced and individually movable and tiltable slats over and applicable to said heating means, and means for applying a uniform pressure to said curtain of slats.

20. In a gluing press, the combination of a relatively flexible heating means applicable over the article to be glued and adapted to conform to the contour thereof, a curtain of parallel, mutually spaced and individually movable slats over and applicable to said heating means, means flexibly supporting said heating means from certain of said slats, and means for applying a uniform pressure to said curtain of slats.

EDWARD J. KLASSEN.
